UNITED STATES PATENT OFFICE

2,664,064

MANUALLY OPERATED BOAT PROPELLING
MECHANISM

Joseph Frank Frenosil, Sr., Moorhead, Minn.

Application January 11, 1952, Serial No. 266,047

3 Claims. (Cl. 115—23)

1

This invention relates to boats and has special reference to a propelling attachment for boats.

One important object of the invention is to provide novel paddle means for propelling a boat, such paddle means being pedal operated by a person in charge of the boat.

The second important object of the invention is to provide, in a device of this character, a paddle attachment for boats of novel character to permit the propulsion of the boat forward or backward as desired and to permit, by the action of the mechanism, the boat to be turned to the left or right as desired.

A further object of the invention is to provide a novel device of this character which can be applied at any place in the length of a rowboat independently of the location of oar locks.

Another object of the invention is to provide a novel device of this character suitable for use either for fishing or for pleasure and either by children or adults, the arrangement being such as to prevent accidental capsizing of the boat.

With the above and other object in view, as will be hereinafter apparent, the invention consists in general of certain novel features of construction and combinations of parts hereinafter fully described, illustrated in the accompanying drawings, and particularly pointed in the claims.

In the drawings like characters of reference indicate like parts in the several views, and in which

Figure 1 is a transverse section to a typical boat hull and showing the present device applied thereto, the view being in section on line 1—1 of Figure 2.

Figure 2 is a fragmentary side elevation of a portion of the boat hull and showing the outboard extending parts of the present device.

Figure 3 is a section on the line 3—3 of Figure 1.

Figure 4 is an enlarged detail of a part of Figure 3, and

Figure 5 is a detail showing a clutch operative mechanism.

As herein disclosed, there is indicated a boat hull having a bottom 10 and sides 11. The upper edges of the sides 11 are provided with gunwales 12.

The attachment for this boat includes a pair of clamping members 13 for each side of the boat and these pairs straddle the gunwales as clearly shown in Figure 1. In order to firmly hold the member 13 in place there is provided for each pair a bolt 14 which passes through the two members 13 and upon being tightened draws these

2

firmly towards each other. At the upper end of each pair of members 13 there is provided an elongated sleeve 15 forming a bearing for a shaft 16.

Fixed centrally on the shaft 16 is a belt pulley 17 shaped to accommodate a V-belt 18 the lower end of which passes around a belt pulley 19.

On the bottom of the boat there is mounted a reinforcing plate 20 whereon is bolted a plate 21 having adjacent one end thereof an elongated eye 22 wherethrough passes a bolt 23. Extending upwardly from the eye 22 is a pair of arms 24. These arms converge upwardly toward a pair of similar arms 25 the lower ends of which rest slidably on the plate 21. Pivotally connected to a bolt 26 joining the arms 25 is an adjusting arm 27 having notches 28 in its lower edge and these notches selectively engage a bolt 29 joining the arms 24. The upper ends of the arms 24 and 25 are connected to the base portions 30 of a pair of standards 31, the upper ends of which are secured to the adjacent ends of sleeves 15.

Now by adjusting the member 27 it will be seen that the lower ends of the arms 24 and 25 can be moved toward or from each other and thereby the standards 31 can be raised or lowered to conform to the position desired for the shafts 16. The base operations of the standards 30 have journaled therein a shaft 32 whereon is fixed the pulley 19. On the ends of the shaft 32 are fixed pedal arms 33 carrying the usual pedals 34.

The shafts 16 extend outwardly beyond the sides 11 of the boat and on these extended ends are slidably mounted clutch members 35

movable into and out of engagement with clutch members 36 fixed to the respective shaft 16. The outer ends of the shaft 16 are provided with collars 37 between which and the clutch members 35 are springs 38 normally holding said clutch members 35 in engagement with the clutch members 36. A shifting bar 39 extends, for each clutch, through eyes 40 fixed to the respective sleeve 15. On the clutch members 35 are fixed sprocket wheels 41 around which pass the chains 42 which extend downwardly and around sprocket wheels 43. The sprocket wheels 43 are mounted on sleeves 44 which rotate on shafts 45 fixed to the lower ends of standards 46 which depend from and are fixed on the outer ends of sleeves 15. On each of the sleeves 45 is mounted a paddle wheel 47 here shown as having four blades although it may have any number of blades desired.

In the operation of the device the operator

actuates the pedals thus causing driving through the belt 18 of the shaft 16 and, so long as the clutches are engaged, also effecting rotation of the paddle wheels which drive the boat. Obviously, the boat will be driven either forward or backward according to the direction of rotation of the pedals. If it is desired to cause the boat to turn to the right, the right hand clutch is disengaged so that all the power is transmitted to the left hand clutch. If it is desired to drive the boat to the left, the left hand clutch is similarly disengaged.

From the above detailed description of the invention, it is believed that the construction, use, and operation thereof will at once be apparent, and while there is herein shown and described the preferred embodiment of the invention, it is nevertheless to be understood that minor changes may be made therein without departing from the spirit and scope of the invention as claimed.

What is claimed is:

1. In combination with a boat hull having a bottom and sides, a propelling mechanism including aligned bearing sleeves, a clamp means carrying said sleeves and adapted to fit over and grip the upper edges of said sleeves, a shaft extending through said sleeves, pedal means connected to the center of said shaft, a pair of paddle wheels, means to support said paddle wheels exterior of the hull at the sides thereof, said shaft having its ends projecting outwardly of the remote ends of said sleeves, a clutch member fixed adjacent each end of said shaft, a cooperating clutch member for each fixed clutch member, means actuated by said cooperative clutch members for driving said paddle wheels, springs urging said cooperating clutch members into engagement with the fixed clutch members, guide eyes fixed on said sleeves at the inner and outer portions thereof, shipper rods engaging said cooperating clutch members and extending inboard of the hull through said guide eyes, and operating handles on the inner ends of said rods.

2. In combination with a boat hull having a bottom and sides, a propelling mechanism including aligned bearing sleeves, clamp means carrying said sleeves and adapted to fit over and grip the upper edges of said sleeves, a shaft extending through said sleeves, pedal means connected to the center of said shaft, a pair of paddle wheels, means to support said paddle wheels exterior of the hull at the sides thereof, said shaft having its ends projecting outwardly of the remote ends of said sleeves, a clutch member fixed adjacent each end of said shaft, a cooperating clutch member for each fixed clutch member,

including hangers fixed to and depending from the outer ends of said sleeves and journals projecting outwardly from the lower ends of said hangers, said paddle wheels having hubs rotatably mounted on said journals, springs urging said cooperating clutch members into engagement with the fixed clutch members, guide eyes fixed on said sleeves at the inner and outer portions thereof, shipper rods engaging said cooperating clutch members and extending inboard of the hull through said guide eyes, and operating handles on the inner ends of said rods.

3. In combination with a boat hull having a bottom and sides, a propelling mechanism including aligned bearing sleeves, clamp means carrying said sleeves and adapted to fit over and grip the upper edges of said sleeves, a shaft extending through said sleeves, pedal means connected to the center of said shaft, means for adjusting the height of said pedal means to and from said bottom, a pair of paddle wheels, means to support said paddle wheels exterior of the hull at the sides thereof, said shaft having its ends projecting outwardly of the remote ends of said sleeves, a clutch member fixed adjacent each end of said shaft, a cooperating clutch member for each fixed clutch member, means actuated by said cooperative clutch members for driving said paddle wheels, springs urging said cooperating clutch members into engagement with the fixed clutch members, guide eyes fixed on said sleeves at the outer and inner portions thereof, shipper rods engaging said cooperating clutch members and extending inboard of the hull through said guide eyes, and operating handles on the inner ends of said rods.

JOSEPH FRANK PRENOSIL, SR.
